(74) Attorney, Agent, or Firm — Edward S. Sherman

(57) **CLAIM**

The ornamental design for a storage container, substantially as shown and described.

DESCRIPTION

FIG. 1 is a perspective view of the “storage container”, showing my new design;

FIG. 2 is a top plan view thereof;

FIG. 3 is a bottom plan view thereof;

FIG. 4 is a side elevation view thereof; and,

FIG. 5 is a cross sectional elevation view thereof that is taken at section line 5-5 in FIG. 2.

1 Claim, 4 Drawing Sheets(56)
